LEAF HOLDER DEVICE

Scipione M. Del Camp, Maywood, Ill., assignor
to Cinch Manufacturing Corporation, Chicago,
Ill., a corporation of Illinois

Application May 8, 1935, Serial No. 20,350

11 Claims. (Cl. 281—25)

My invention aims to provide an improved leaf holder for checks, sales slips and the like.

In the drawing which represents preferred embodiments of my invention:

5 Figure 1 is a fragmentary plan view of a binding cover with two of my U-shaped holding members attached to a portion of the cover;

Fig. 2 is a longitudinal section taken along the line 2—2 of Fig. 1;

10 Fig. 3 is a fragmentary transverse section taken along the line 3—3 of Fig. 1;

Fig. 4 is a side view of one of my U-shaped holding members;

Fig. 5 is a bottom plan view of my fastening 15 plate;

Fig. 6 is a bottom plan view of my fastening plate with my U-shaped holding member in locked engagement;

Fig. 7 is a top plan view of my fastening plate;

20 Fig. 8 is a fragmentary plan view of a leg of my U-shaped holding member;

Fig. 9 is a side view of a holding member, a modified form of attachment to a cover portion being shown in section; and

25 Fig. 10 is a longitudinal section of my U-shaped holding member with my modified form of attachment to a cover portion.

Referring to the drawing, I have shown in Fig. 1 a binding cover having a front portion 1 and 30 a back portion 2 which are hinged to an intermediate end portion 3 in any suitable manner.

Attached to one portion of the cover, and in my preferred form I have chosen the back portion 2, I have provided a pair of U-shaped holding members 4 which are substantially U-shaped in cross-section, the open portion being outermost. Said U-shaped holding members have the legs 5 and 6 joined together by the curved bridge portion 7. Portions have been cut away from the free edges of the legs to form T-shaped attaching elements at the termination of said legs, said attaching elements comprising, in my preferred form, a bow-shaped head portion 8 and 45 a neck portion 9 which joins the portion 8 to the legs, as shown in Figs. 4 and 8.

The attaching elements are formed integral with the legs 5 and 6 and extend in the same plane therefrom, and shoulder portions 10 are formed on the legs 5 and 6 at the junction of said legs with the neck portions 9.

As a means of attaching my U-shaped holding members to the cover portion 2, I have provided 50 the sheet metal fastening plates 11 and 11' which

are located adjacent to each side of the cover portion 2, as shown in Figs. 2 and 3.

The fastening plates, as illustrated in Figs. 5 and 7, are identical in form, are preferably rectangular in shape and have the pairs of embossments 12 and 12' pressed outward, said embossments being located at a spaced distance apart. Substantially in the center of the embossments 12 and 12', I have cut out the apertures 13 and 14 which are bow-shaped in my preferred form and placed in spaced position to receive the bow-shaped head portions 8 of the attaching elements.

To fasten the U-shaped member 4 to the cover portion 2, the head portions 8 are extended through the upper plate 11, the cover portion 2 and the lower plate 11', and then, with a suitable tool, the bow-shaped head portions are substantially straightened with the result that they will bear upon the walls surrounding the apertures 13 and 14 of the plate 11', as shown in Fig. 6. The shoulders 10 of the legs 5 and 6 will then bear firmly upon the upper plate 11 and the holding members will be securely fastened to the cover, as shown in Figs. 3 and 4.

Due to the embossments 12 and 12', the head portions 8 will not extend beyond the plane of the plate 11' after attachment thereby providing the open face of said lower plate with a relatively smooth surface.

In assembling the component parts of my leaf holding device, I prefer to cut from the cover 2 two pairs of apertures, each of said pairs being located at a spaced distance apart on said cover, the apertures of each individual pair being spaced apart to correspond with the apertures 13 and 14 of the fastening plates 11 and 11'. A plurality of sheets, which I have not shown in my drawing, are perforated in the usual manner and assembled with one leg of each of the two U-shaped members which I have chosen to represent a preferred form of my invention. The plates 11 and 11' are then placed in position in relation to the apertures in the cover 2, and the U-shaped members, together with the sheets they carry, are permanently fastened to the cover 2 in the manner which has been described.

Although I have preferred to attach only two of the U-shaped members to the cover, it is understood that as many of these may be employed as desired. Also, though I have chosen a binding cover to illustrate my invention, I do not wish to limit myself thereby, but realize that the U-shaped members could be attached to any

suitable support which would carry out a practical application of my invention.

In Figs. 9 and 10, I have illustrated a modification of my invention. In this form I have chosen 5 to place one attaching plate 11 adjacent to the side of the apertured binder cover 2 opposite the U-shaped holding member 4. The legs of the U-shaped member are extended through the apertures of the cover 2 and fastened to the 10 plate 11 in the manner which has been described. A covering material 15 is hinged to a portion of the binder cover and extended over the lower face of the plate 11 and then fastened to the binder cover in any suitable manner there- 15 by hiding the lower face of the attaching plate and giving the binding a neat and attractive appearance.

While I have illustrated and described preferred embodiments of my invention, I do not 20 wish to be limited thereby, because the scope of my invention is best defined by the following claims.

I claim:

1. A leaf holder comprising a supporting material, a U-shaped holding member associated with said supporting material, the opposite legs of said U-shaped member extending downwardly toward said material and having attaching elements formed integral with said legs, each of said attaching elements comprising a head and a neck portion, said neck portion joining said head portion to its corresponding leg, shoulders formed on said legs at corresponding points, plate means associated with and secured to said supporting material and said U-shaped holding member, said plate means having slot-shaped apertures at pre-determined points and designed to receive the head portions of said attaching elements, said head portions projecting through the apertures 30 of said plate means and being turned whereby said head portions will bear upon the material of one surface of said plate means adjacent to the apertures therethrough, and said shoulders engaging the opposite surface of said plate means thereby attaching said U-shaped member in position relative to said supporting material.

2. A leaf holder comprising a piece of supporting material, a plurality of U-shaped channeled holding members located on said supporting material at a spaced distance apart, the opposite legs of said U-shaped members extending downward toward said material and having attaching elements formed integral with said legs, each of said attaching elements comprising a head and a neck portion, said neck portions being intermediate said head portions and said legs, shoulders being formed on said legs at corresponding points, and metal plates adjacent to each side of said supporting material, each of said plates having slot-shaped apertures at corresponding points, said apertures designed to receive the head portions of said attaching elements, said head portions projecting through said plates and apertures in said material and turned whereby said head portions 50 will bear upon the walls surrounding the apertures of said lower plates and the shoulders of said legs will bear firmly upon said upper plates thereby attaching said U-shaped members to said supporting material.

3. A leaf holder comprising a piece of supporting material, a plurality of U-shaped channeled holding members located on said supporting material at a spaced distance apart, the opposite legs of said U-shaped members extending 55 downward toward said material and having at-

taching elements formed integral with said legs, each of said attaching elements comprising a head and a neck portion, said neck portions being intermediate said head portions and said legs, shoulders being formed on said legs at corresponding points, metal plates adjacent to the side of said supporting material opposite said U-shaped members, said plates having slot-shaped apertures designed to receive the head portions of said attaching elements, said head portions projecting through apertures in said supporting material and said plates and turned whereby said head portions will bear upon the walls surrounding said apertures and the shoulders of said legs will bear firmly upon said plates thereby attaching said U-shaped members to said supporting material, and a piece of material extending over the open face of said plates, said material being hingedly connected to said supporting material.

4. A leaf holder comprising a cover having front, back and intermediate end portions hingedly connected together, a plurality of U-shaped channeled members made of sheet metal located on said cover at a spaced distance apart, the opposite legs of said U-shaped members extending downward toward said cover and having attaching elements formed integral with said legs and lying in the same plane thereof, each of said attaching elements comprising a head portion of bow-shaped cross-section and a neck portion, said neck portions joining said head portions to said legs, shoulders being formed on said legs at corresponding points, and sheet metal plates adjacent to each side of said cover, said plates provided with embossments and having bow-shaped apertures cut in said embossments designed to receive the head portions of said attaching elements, said head portions projecting through said plates and apertures in said cover and straightened substantially whereby said head portions will bear upon the walls surrounding the apertures of said lower plates and the shoulders of said legs will bear firmly upon said upper plates thereby attaching said U-shaped members to said cover.

5. A leaf holder comprising a cover having front, back and intermediate end portions hingedly connected together, a plurality of U-shaped channeled members made of sheet metal located on said cover at a spaced distance apart, the opposite legs of said members extending downward toward said cover and having attaching elements formed integral with said legs and lying in the same plane thereof, each of said attaching elements comprising a head portion of bow-shaped cross-section and a neck portion, said neck portions joining said head portions to said legs, shoulders being formed on said legs at corresponding points, sheet metal plates adjacent to the side of said cover opposite said U-shaped members, said plates provided with embossments and having bow-shaped apertures cut in said embossments designed to receive the head portions of said attaching elements, said head portions projecting through apertures in said cover and said plates and straightened substantially whereby said head portions will bear upon the walls surrounding the apertures of said plates and the shoulders of said legs will bear firmly upon said plates thereby attaching said U-shaped members to said cover, and a piece of material extending over the open face of said plates, said material being hingedly connected to said cover.

6. An article of manufacture for use as a leaf fastener comprising a U-shaped member having 75

side legs, attaching elements formed integral with the free ends of said side legs and each shaped to provide a head portion and a neck portion, said neck portions being adapted to receive fastener-supporting means between the ends of the legs and the heads, and the said heads being twistable to secure the fastener to the supporting means.

7. An article of manufacture for use as a leaf fastener comprising a U-shaped member having side legs, attaching elements formed integral with the free ends of said side legs, each of said attaching elements comprising a head portion of substantially bow-shaped cross-section and a neck portion, said neck portions joining said head portions to said legs, shoulders being formed on said legs at corresponding points, said neck portions being adapted to receive fastener-supporting means between the ends of the legs and the heads, and said heads adapted to being substantially straightened to secure the fastener to the supporting means.

8. An article of manufacture for use as a leaf fastener comprising a U-shaped member of channelled cross-section having side legs, attaching elements formed integral with the free ends of said side legs and lying in the plane of said legs, each of said attaching elements comprising a head portion of bow-shaped cross-section and a neck portion, said neck portions being intermediate to said head portions and said legs, shoulders being formed on said legs at corresponding points, said neck portions being adapted to receive fastener-supporting means between the ends of the legs and the heads, and said heads adapted to being substantially straightened to secure the fastener to the supporting means.

9. Articles of manufacture for use as a leaf fastener comprising a U-shaped member having side

legs, attaching elements formed integral with the free ends of said side legs and each shaped to provide a head portion and a neck portion, and a metal plate, said head portions projecting through apertures in said plate and twisted to secure the fastener member to the plate.

10. Articles of manufacture for use as a leaf fastener comprising a U-shaped member having side legs, attaching elements formed integral with the free ends of said side legs, each of said attaching elements comprising a head portion of substantially bow-shaped cross-section and a neck portion, said neck portions joining said head portions to said legs, shoulders being formed on said legs at corresponding points, and a metal plate having bow-shaped apertures at corresponding points, said head portions projecting through said apertures and substantially straightened whereby said head portions will bear upon the walls surrounding said apertures thereby securing the fastener member to the plate.

11. Articles of manufacture for use as a leaf fastener comprising a U-shaped channeled member having side legs, attaching elements formed integral with the free ends of said side legs, each of said attaching elements comprising a head portion of substantially bow-shaped cross-section and a neck portion, said neck portions joining said head portions to said legs, shoulders being formed on said legs at corresponding points, and a metal plate provided with embossments and having bow-shaped apertures cut in said embossments, said head portions projecting through said apertures and substantially straightened whereby said head portions will bear upon the walls surrounding said apertures thereby securing the fastener member to the plate.
